UNITED STATES PATENT OFFICE.

CHARLES THOMAS CROWDEN, OF LEAMINGTON SPA, ENGLAND.

APPARATUS FOR MAKING TUBULAR JOINTS.

SPECIFICATION forming part of Letters Patent No. 609,734, dated August 23, 1898.

Application filed March 14, 1898. Serial No. 673,861. (No model.)

To all whom it may concern:

Be it known that I, CHARLES THOMAS CROWDEN, a subject of the Queen of England, residing at Leamington Spa, England, have invented certain new and useful Improvements in Apparatus for Making Tubular Joints, (for which I have made application in England under No. 6,540, dated March 12, 1897,) of which the following is a specification.

This invention relates to the making of tubular joints where one tube is placed inside another tube and parts of the two are forced into each other by direct hydraulic pressure.

15 In my previous British applications, No. 22,721 of 1895 and No. 13,577 of 1896, I have described various ways of making joints of this description. My present invention relates to the apparatus and the manner of operating it.

20 In carrying out my present invention I employ a suitable jig or mold, into which the parts of the joint or joints are placed, or, if desired, a complete framework of a cycle, for 25 example, may be placed in a suitable jig and all the joints made at once. The jig must be divided where necessary to give access to the interior for the insertion or removal of the parts to be joined, and in my previous 30 applications I indicate the fastening of the various parts of the mold together by means of bolts. By my present invention I do not hold the parts together by bolts, but by hydraulic pressure. I employ a suitably-constructed hydraulic press, and to the base or 35 fixed table of this I secure one or more parts of the jig, and to the head of the ram or movable table I secure another part or parts. When the pressure is applied, the ram descends and brings the two parts of the mold together, the pressure of the ram holding them 40 in tight contact. The pressure for making the joints may be then applied in substantially the manner already described in said previous 45 applications.

If desired, the press may be made in more than two parts, and more than one ram and more than one fixed part may be employed. For instance, where it is desired to remove a 50 particular portion of the frame in a direction other than that of the axial line of the press I may have another ram operating in a path,

say, perpendicular to that of the first ram, so as to draw a particular portion or portions of the jig or mold out in the required direction. 55

The portions of the jig may be bolted to the respective portions of the press, or they may be merely fitted in and held by any convenient means. In the case of the bottom portion no special means are necessary for holding the jig, as it is merely necessary that it should be fitted upon the table in the proper position. In the movable parts, where the part of the jig would have to be raised, means sufficient to overcome the weight of the portion of the jig which was raised would be necessary. 60

65 One valve or set of valves may be employed for operating the rams and another valve or set of valves for controlling the pressure for making the joints, or the same valve or valves may be arranged to control the whole of the pressure. 70

In the accompanying drawings, Figure 1 is an elevation, partly in section, of the improved apparatus employed for making tubular joints. Fig. 2 is a plan of the same. Fig. 3 is a view showing the main lower die in plan and the supplemental die in section, taken on the dividing-line of the main dies, 80 with a portion of the bicycle-frame shown in position in the dies. 75

Like letters indicate like parts throughout the drawings.

Above a table A is arranged a cylinder B, 85 in which is a hydraulic ram C, connected to a movable table C'. On the inner end of the ram C is an extension C², which passes through into a small cylinder B' on the end of the cylinder B, being there provided with a piston 90 C³. A low-pressure main D leads into a connecting-piece E, being provided at its point of entrance with a back-pressure valve D'. 95

From the connecting-piece E lead three pipes, one F passing through the cylinder B', a second pipe G being connected to the high-pressure hydraulic main H and to the cylinder B, while a third pipe J leads to the interior of the jig or mold and communicates with the interior of the articles to be united. 100

The two main parts K K' of the jig or mold are attached to the fixed table A and movable table C', respectively.

A three-part jig is shown in the example,

the subsidiary part K² being acted upon by a ram L in a cylinder L'.

To operate the apparatus, the high-pressure main is shut off, low-pressure water being admitted through the pipe D and valve D', pipe F, and cock-valve F' into the cylinder B', the pressure being admitted below the piston C³, and consequently raising the table C' with the part K' of the jig attached to it. The article to be jointed is placed in the part K of the jig, and the table C', with the second part K' of the jig, brought down onto the fixed part K.

Water under high pressure is now admitted to the interior of the cylinder B and through pipe J to the interior of the sections of the joint to be made contained within the die-cavity of the mold, thereby forcing the joint-sections into union, the hydraulic ram C holding the sections of the mold together against the pressure exerted in forcing the joint-sections into union.

If a three or more part jig is employed, power is admitted to the supplementary cylinder or cylinders at the same time as to the main cylinder B.

It is to be noted that the cross-sectional area of the ram C is greater than the corresponding interior portion of the mold or jig which is subjected to the like hydraulic pressure as the ram.

It is not necessary to employ low-pressure water for raising the ram and part of the jig so long as the operation is performed hydraulically.

It is to be understood that the details of the apparatus may be varied in accordance with requirements without departing from the spirit of the invention.

Having now particularly described and ascertained the nature of the said invention and in what manner the same is to be performed, I declare that what I claim is—

In an apparatus such as described the combination with the sectional mold having the die-cavity of the shape to receive the sections of the joint to be made, formed in the adjacent faces of the mold-sections, with means for supplying hydraulic pressure to the interior of the joint-sections contained in the die-cavity and a hydraulic ram for holding the mold-sections together against the pressure exerted in forcing the joint-sections contained in the die-cavity into union; substantially as described.

In testimony whereof I have hereto set my hand in the presence of the two subscribing witnesses.

CHARLES THOMAS CROWDEN.
